UNITED STATES PATENT OFFICE.

ROBERT C. ANDERTON, OF SAN FRANCISCO, CALIFORNIA, ASSIGNOR OF ONE-HALF TO
GEORGE H. PIPPY, OF SAN FRANCISCO, CALIFORNIA.

LOCK FOR EXPLOSION ENGINES.

1,410,443.

Specification of Letters Patent. Patented Mar. 21, 1922.

Application filed April 20, 1920. Serial No. 375,280.

To all whom it may concern:

Be it known that I, ROBERT C. ANDERTON, a citizen of the United States, residing at San Francisco, in the county of San Francisco, State of California, have invented a new and useful Lock for Explosion Engines, of which the following is a specification in such full and clear terms as will enable those skilled in the art to construct and use the same.

This invention relates to a lock for the ignition system of explosion engines and its object is to provide means whereby the car owner may prevent the operation of the car in such a manner as to make it substantially impossible to operate the car by unlawful tampering with the ignition system.

It will be understood by those skilled in the art, that in the operation of multiple cylinder engines that use the jump spark ignition system, that a single wire extends from the spark plug to the magneto, or other spark producing apparatus and that the sparks must occur on the several spark plugs in a particular order in order for the engine to be operated.

In the present instance means is provided to prevent the operation of the sparking system, which means is permanently attached to some convenient portion of the car, and if the ignition system is cut in two to eliminate this lock, a considerable amount of time must be taken up in ascertaining the proper relation of the spark producing apparatus to the series of engine cylinders in order to run the engine, so that the likelihood of the car being stolen by cutting out or eliminating this locking system, is remote.

Another object of the invention is to provide means whereby the car driver may ascertain at a glance if the spark plugs are all operating properly, and to immediately ascertain which individual spark plug is not operating as it should in order to renew it or to correct the difficulty.

Other objects of the invention will appear as the description proceeds.

An embodiment of the invention is shown in the accompanying drawings in which the same reference numeral is applied to the same portion throughout, but I am aware that there may be modifications thereof.

Figure 1 is a perspective view of a portion of the engine showing the ignition system and this lock applied thereto.

Fig. 2 is a vertical sectional view of this locking device.

Fig. 3 is a front elevational of this locking device.

Fig. 4 is an end elevation of the locking device.

Fig. 5 is a transverse sectional view of the locking device and showing it as it appears applied to the dashboard of the car.

The numeral 1 indicates the engine cylinder block, 2 the magneto and 3 the series of cables which extend to the lock casing 4. From the lock casing 4 a series of cables 5 return to the engine and connect with the several spark plugs as indicated at 6 to 11 inclusive. The engine shown has six cylinders, although the invention is applicable to an engine having any number of cylinders.

The lock casing comprises a fibre cylinder having holes 12 to 15 inclusive, through which the bolts 16 are passed to secure the lock to the dashboard 17 of the vehicle. The fibre cylinder is provided with a glass front 18 through which the spark points 19 and 20 of which there are six opposed pairs, one pair for each of the magneto wires can be seen and which sparking points are separated sufficiently to allow the fibre plate 21 to pass between them.

The fibre plate 21 slides in grooves 22 and 23 in the cylinder 4 and the slide is movable on an arm 25 on the end of the cylinder. The arm 25 has a hole 26 therein and the slide 21 has a hole 27 to receive the shackle 28 on a padlock 29, although the kind of lock used forms no part of the invention.

When the car is to be operated, the slide 21 is removed to the position indicated in Fig. 2, at which time the sparks are free to pass from the points 20 to the points 19 of the entire series, and they are jumped across these points as well as across the points of the spark plugs.

When the car is to be locked against operation the slide 21 is moved to the position shown in Fig. 3, thereby preventing the sparks from passing from the points 20 to the points 19 and of course preventing the sparks from passing across the points of the several spark plugs.

Since it is difficult to ascertain in a few minutes the proper relationship of the wires 3 to the several series of wires 5, it is very difficult to operate the car by eliminating the locking cylinder 4 from the ignition circuit.

This being accomplished only after a considerable amount of testing of the firing order of all of the cylinders of a given engine.

5 By separating the points 19 and 20 as indicated, the intensity of the spark on the spark plugs is increased and, at the same time, if any spark plug does not operate properly, that fact is indicated by an examination of the sparks made on the points 10 19 and 20.

What I claim is as follows, but various modifications may be made in the construction shown in the drawings and above particularly described form, within the purview 15 of my invention.

1. An ignition lock for explosion engines comprising an insulated block, a series of 20 sparking electrodes carried thereby, wires connecting said electrodes with the source of electric current and with the spark plugs respectively, an insulating slide adapted to pass between the ends of the pairs of electrodes to prevent the current from passing 25 between said electrodes and a lock for preventing the removal of said insulating means at will.

2. An ignition lock for explosion engines comprising an insulated block, a series of 30 pairs of sparking electrodes carried thereby, said block having a window for observing

the same, wires for connecting said electrodes with the source of electric current supply and with the spark plugs respectively, and an insulating slide adapted to pass between 35 the ends of the pairs of electrodes to prevent the current from passing between said electrodes.

3. An ignition lock for explosion engines comprising an insulated block, a series of 40 pairs of sparking electrodes carried thereby, a window along the front of said block for observing the condition of sparking of all of the said electrodes, wires connecting said electrodes with the source of electric current 45 supply and with the spark plugs respectively, an insulated slide adapted to move between all of said electrodes to prevent them from sparking and a lock for securing said slide in said position to prevent the operation of 50 the engine.

4. An ignition lock for explosion engines comprising a support, a series of pairs of 55 sparking electrodes carried thereby, wires for connecting said electrodes with a source of electric current supply and with the spark plugs of the engine, and manually operated means to prevent the current from passing between said electrodes.

In testimony whereof I have hereunto set 60 my hand this day of April A. D. 1920.

ROBERT C. ANDERTON.
